Shirley McLarty, Dallas, Tex.

Application March 18, 1957, Serial No. 45,311

Term of patent 14 years

(Cl. D34—15)

Fig. 1

Fig. 2

Fig. 3

Fig. 4

Figure 1 is a front elevational view of a wind propelled spinner or similar article, showing my new design;

Figure 2 is an edge elevational view;

Figure 3 is an end elevational view; and

Figure 4 is a perspective view thereof.

The rear, other edge and other end, not shown, have substantially the same appearance, respectively, as the front, edge and end shown in the figures.

I claim:

The ornamental design for a wind propelled spinner or similar article, substantially as shown and described.
